UNITED STATES PATENT OFFICE

105,134

DESIGN FOR A SPOON OR ANALOGOUS ARTICLE

Harold E. Nock, Newburyport, Mass., assignor to Towle Manufacturing Company, Newburyport, Mass., a corporation of Massachusetts

Application December 23, 1936, Serial No. 66,708

Term of patent 14 years

To all whom it may concern:

Be it known that I, Harold E. Nock, a citizen of the United States, residing at Newburyport, in the county of Essex and Commonwealth of Massachusetts, have invented a new, original, and ornamental Design for a Spoon or Analogous Article, of which the following is a specification, reference being had to the accompanying drawing, forming a part thereof.

In the accompanying drawing Figure 1 is a front elevational view of a spoon showing my new design; and Figs. 2, 3 and 4 are sectional views of the handle taken on the lines 2-2, 3-3 and 4-4, respectively, of the handle shown in Fig. 1.

The dominant feature of my design is the orna-

mental handle for flatware the dotted lines on the drawing indicating the conventional bowl of a spoon.

The design is delineated as embodied in the handle of a spoon but the design may also be embodied in or applied to the handles of forks, knives, servers and other analogous pieces of flatware which may form a part of a table service of uniform pattern.

I claim:

The ornamental design for a spoon or analogous article, substantially as shown and described.

HAROLD E. NOCK.
